Primary Examiner — Jennifer O King(74) *Attorney, Agent, or Firm* — Vorys, Sater, Seymour and Pease LLP; William L. Klima(57) **CLAIM**

The ornamental design for a battery terminal, as shown and described.

DESCRIPTION

FIG. 1 is a perspective view of a new design for a battery terminal;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown represent portions of the battery terminal that form no part of the claimed design.
